UNITED STATES PATENT OFFICE.

ANDREW J. ASCH, OF NEW YORK, N. Y.

RHEOSTAT.

1,187,228.

Specification of Letters Patent. Patented June 13, 1916.

Application filed February 12, 1916. Serial No. 77,928.

To all whom it may concern:

Be it known that I, ANDREW J. ASCH, a citizen of the United States, and a resident of the city of New York, borough of Manhattan, in the county and State of New York, have invented a new and Improved Rheostat, of which the following is a full, clear, and exact description.

This invention relates to rheostats especially adapted for treatments by the cataphoresis and ionization methods, although the invention is not necessarily limited to this use.

The invention has for its general objects to improve the construction and operation of rheostats so as to be reliable and efficient in use, comparatively simple and inexpensive to manufacture, and so designed as to enable very fine adjustments for small variations in current strength.

A more specific object of the invention is the provision of a rheostat of the coil type in which a contact slider makes contact with the convolutions of the coil to thereby vary the effective length of the resistance of the circuit, the movement of the slider being effected by a micrometer screw from which the slider can be disengaged whenever desired, for effecting a quick adjustment or the bringing of the slider back to its initial position.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views, Figure 1 is an elevation of the device; Fig. 2 is a rear view; Fig. 3 is a transverse section on the line 3—3, Fig. 2; and Fig. 4 is a detail view of the slider.

Referring to the drawing, A designates the casing of the rheostat which comprises a three-sided shell 1 open at both ends and at one side, and in the ends are disposed blocks 2 of insulation which are secured to the shell by screws or equivalent fasteners 3. If the device is to be applied to a panel, bolts 4 are anchored in or fastened to the end blocks 2. Each end block has an opening 5 for holding a brass or other non-magnetic tube which forms the support for the resistance coil or helical winding 7, there being mica interposed between the core or support 6 and the winding. The coil is made of very fine wire with a film of enamel coating, so that the wire can be wound with its convolutions close together to insure a great length of resistance wire within a small compass. The terminals 9 and 10 of the coil are connected by screws 11 and 12 to the blocks 2, and these screws are grounded on adjacent bolts 4 to which circuit wires are to be connected.

To vary the effective length of the resistance coil a movable contact is employed to move in engagement with the successive convolutions. This contact device comprises a slider B which is a block having openings 13 and 14 through which extend a fixed guide rod 15 and a rotary screw 16, both of which are mounted in the end blocks 2 of the casing. On the slider are spring contact members 17 which bear against the coil, the insulation of which is removed at the points where the contacts 17 engage with the coil. On the slider B is a lever 18 fulcrumed on the guide rod 15, and this lever has an opening 19 which is threaded so as to mesh with the threads of the screw, engagement of the threads of the lever with the screw being maintained by a spring 20 fastened to the body of the slider and pressing upwardly on the lever, as shown in Fig. 3. The lever has a stem or shank 21 extending out of a longitudinal slot 22 in the casing, and on this stem is a knob 23 whereby the lever can be depressed to disengage it from the screw, and then, while held depressed, moved laterally to shift the contacts to any desired point on the coil. The screw 16 is employed for effecting a very fine adjustment of the slider and thereby enable nice variations of current strength to be obtained, the screw being turned by means of a knurled knob or equivalent means 24 fastened to the screw at one end. The guide rod 15 has one end connected by a wire 25 with one of the bolts 4, so that the slider can be connected with the electric circuit. Thus, in operation, either one of the ends of the coil is connected with one side of the circuit and the slider with the other side, and by adjusting the position of the slider through the turning of the screw, any desired amount of resistance can be cut into or out of the circuit.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. A rheostat comprising a casing, a resistance coil mounted therein, a guide rod in the casing extending longitudinally along the coil, a screw rotatably mounted in the casing and disposed parallel with the guide rod, a slider movable along the rod, contact means on the slider for engaging the convolutions of the coil, a movable element mounted on the slider and having threads for engaging the screw whereby the rotation of the latter moves the slider, means for yieldingly holding the element in engagement with the screw, said element having a portion extending out of the casing for permitting the operator to release it from the screw and effecting a quick adjustment of the slider, and means for connecting the slider and a terminal of the coil to an electric circuit.
2. A rheostat comprising a casing formed of a shell having an open side and open ends,

blocks of insulation fastened in the ends, a non-magnetic tube fastened in the blocks, a helical resistance coil carried by the tube, a slider movable along the tube, a support carrying the slider, contact means on the slider for engaging the convolutions of the coil, an operating screw rotatably mounted in the end blocks, means for turning the screw, and means on the slider for engaging the screw to cause the slider to move by the rotation of the screw.

3. A rheostat comprising a casing formed of a shell having an open side and open ends, blocks of insulation fastened in the ends, a non-magnetic tube fastened in the blocks, a helical resistance coil carried by the tube, a slider movable along the tube, a support carrying the slider, contact means on the slider for engaging the convolutions of the coil, an operating screw rotatably mounted in the end blocks, means for turning the screw, a lever operatively connected with the slider and having threads normally engaging the screw, and a spring on the slider and pressing on the lever for maintaining it in engagement with the screw, said casing having a slot through which the lever extends for enabling the operator to release the lever and move the same, together with the slider, independently of the screw.

In testimony whereof I have signed my name to this specification in the presence of two subscribing witnesses.

ANDREW J. ASCH.
